CORRECTIONAL FOOT APPLIANCE

Dante V. Mazzocco, New York, N. Y., assignor to
William Mazzocco, Rio Janeiro, Brazil

Application October 16, 1933, Serial No. 693,811

3 Claims. (Cl. 36—71)

This invention relates to correctional foot appliances of the type to be worn in a shoe and including an arch support having an elevated part to underlie and properly raise a fallen arch 5 or otherwise correct a defective bone situation.

As is well-known, the bones of the human foot comprise at about the rear third of the foot a collection of heel or tarsal bones, at about the middle third of the foot a collection of metatarsals 10 or arch bones, and at about the front third of the foot a collection of bones including the phalanges and the anterior metatarsals. What has apparently not heretofore been recognized is the fact that practically always these three groups 15 of the twenty-six bones of the foot have such important cross-reactions that a defective condition of one group usually entails a similar condition in one or both of the other groups, with seldom or ever the metatarsal bones of the main 20 arch free of defect when one or both of the other two groups are defective. If the defective foot condition sought to be relieved is to be actually 25 gradually corrected rather than aggravated by the wearing in the shoe of a so-called arch support over an extended period, such appliance must in practically every case be carefully 30 designed not only to provide a main support for the metatarsal or main arch bones, but at the same time an auxiliary support for the latter 35 present as an anterior metatarsal support, and also a further auxiliary support present as a tarsal or heel support, with each and every one of these three supports of precisely the proper 40 height and contour, and, moreover, spaced accurately widthwise as well as lengthwise of the 45 foot.

Previous so-called arch-supports have been of two general types. One is the cast plate usually 50 of aluminum or some light metal composition 40 which is formed from a plaster cast of the bottom of the foot. Such castings are bulky, rigid, uncomfortable and very expensive. A casting thus made, moreover, is not at all adjustable during use, and after it has been worn for some time, 55 and foot discomfort is again had, there is nothing to do but to discard the same and have a new plaster cast and a new plate made. Another type of so-called arch-support is that which is kept 60 in stock, in various foot sizes; but the fitting of 65 the same usually involves solely the selection of a raised portion which is so shaped and located 70 thereon as to underlie and elevate a single group of bones, as those forming the main arch, or a 75 bone or bones of the anterior metatarsal group. 80 An object of the present invention is to pro-

vide a foot appliance which is truly correctional 85 because readily variously adjustable all over where required and thus very much more efficient, yet which is of low first and subsequent cost because it can be supplied from stock, then fitted accurately and properly to the patient's foot all over the under-surface thereof, and from time to time thereafter easily and quickly readjusted to take care of changes caused by continued 90 wearing of the appliance.

Another object is to provide such an appliance, to be, say, one of a series of appliances of different foot sizes to be kept in stock; wherein there is a plate or equivalent structure to present a main-arch support somewhat higher than is provided in the ordinary stock plate for the same 95 foot size, in combination with a plurality of auxiliary supports, one for the tarsal bones and the other for the anterior metatarsals, which are independently adjustable on said plate as their carrier when the device is first fitted and also at any time thereafter, to vary the levels of one or both thereof and/or to shift the location of one or both thereof relative to the location of said main-arch support so as to arrange the entire 100 upper contour of the device to adapt the same precisely to that needed to give the most immediately comfortable and otherwise advantageous support for the entire foot bottom, and so as, when required, to diminish the effective 105 elevation of the main-arch support, which is, as previously stated made higher than usual.

Another object is to provide a foot correctional device as above described, wherein one or more 110 of the auxiliary supports is adjustable to vary the relative spacing of the three supports laterally as well as longitudinally of the device.

Another object is to provide a foot correctional device as above described, wherein one or more 115 of the auxiliary supports are so shaped and adjustable that portions thereof of different heights may be selectively placed as desired.

Another object is to provide a foot correctional device as above described, wherein said auxiliary supports are readily demountable from and 120 mountable on the device, so that an auxiliary support of a certain shape or size can be at any time readily substituted for another of a different shape or size.

Another object is to provide a foot correctional 125 device as above described, wherein a side marginal portion of the carrier is shapable to modify the device to adapt it to one of several foot-widths in coaction with modification of the device by adjustment of one or both of the auxiliary 130

supports to adapt said device to one of several foot-lengths.

In a now approved form of the invention, the device has the aforesaid carrier in the form of a die-stamped or pressed sheet metal plate, say aluminum of about 12 to 14 gauge, or spring steel of somewhat thinner gauge, having intermediate its length a raised portion to constitute a main-arch support as aforesaid; the auxiliary supports are pads or cushions rotationally adjustable on the front and rear ends of said carrier; and, desirably, in order to have to provide only comparatively few appliances of different carrier sizes, said carrier is deformable by bending or curling the same upwardly at one or both sides to vary the width of the appliance to adapt the same to fit a wider or thinner foot of a certain approximate length. In this approved form of the device, the auxiliary supports, which can be of any shape or shapes, such as oval or even wedge-shaped, but which are preferably circular or substantially circular in outline, are some of them of uniform heights around their axes of rotation, while others are of varying heights around their axes of rotation; and various of them may vary as to their sizes; and of any two selected as those required to give the device the needed upper contour all over the latter as the result of giving these two proper fractional rotational adjustments on the carrier, one can be so mounted on the carrier as to have its axis of rotational adjustment concentric or variously eccentric thereto, and the other can be so mounted as to have its axis of rotational adjustment concentric thereto or eccentric thereto also in any one of a plurality of different manners and extents of eccentricity.

The invention will be more clearly understood, and the various objects and advantages thereof fully appreciated, from the following description of a now preferred but merely illustrative embodiment thereof as shown in the accompanying drawing, in which

Fig. 1 is a top plan view of said embodiment;
Fig. 2 is a longitudinal vertical section taken on the line 2—2 of Fig. 1;

Fig. 3 is a fragmentary view, being a bottom plan of the front part of the appliance;

Fig. 4 is a transverse vertical section taken on the line 4—4 of Fig. 1; and

Fig. 5 is a transverse vertical section taken on the line 5—5 of Fig. 1.

Similar reference characters refer to similar parts throughout the several views of the drawing.

Referring now to the drawing more in detail, at 10 is indicated a sheet metal carrier, including a forepart to extend under the ball of the foot and having adjustably mounted thereon a cushion or pad 11 constituting the auxiliary support under the anterior metatarsal bones; a rear part to extend under the heel of the foot and having adjustably mounted thereon a cushion or pad 12 constituting the auxiliary support under the tarsal or heel bones; an intermediate part bent upwardly to have a suitable shaping longitudinally and laterally of the carrier to present a main-arch support 10a somewhat higher than usual; a longitudinally extending ear or lip 10b at one side of the carrier alongside said support 10a; and a similarly extending but smaller ear or lip 10c on the opposite side of the carrier and at a point about opposite the forward end of the auxiliary support 12.

As said carrier is now preferred to be made,

it is constructed of spring steel of a suitable light gauge to give the proper strength and resistance to permanent deformation while in use, to permit bending as required of the ears or lips 10b and 10c, and yet to have the entire carrier of the proper resiliency to provide somewhat of a spring mounting for all three supports 10a, 11 and 12 while the device is in use. The lip 10b is provided so as when required to be bent or curled upwardly, more or less, by hand or by a suitable forming tool preferably hand-operated, to fit an appliance of standard length to any particular foot appropriate to that length once the supports, or pads 11 and 12 as they will hereinafter be called, are properly adjusted on the carrier; and the lip 10c is provided for being similarly reshaped when an additional modifier of the shape of the appliance, or of its manner of lie in the shoe, is advisable. In some cases, of course, as will be understood, one or both of these lips will be bent outwardly rather than upwardly, as various types of feet and footwear are encountered.

The pads 11 and 12 may be constructed in any suitable manner, and of any suitable material or materials; but are here shown as being each made up of a backing of thin sheet metal, a padding of felt, rubber or some other cushioning material, and a covering of leather or the like,—said backing, padding and covering being respectively marked in Fig. 2 as 14, 15 and 16.

Each of the pads 11 and 12 is rotationally adjustable on the carrier, and securable in the selected adjustment, quickly and easily, all by means of a screw 17 extended upwardly through a hole in the carrier and threadedly engaging a tapped hole in the backing of the pad. On merely loosening its screw 17, either pad can be fractionally rotated to any extent desired, and then locked in that adjustment by merely tightening said screw. For either pad, a replacement pad of any height, outline shaping or upper-contour shaping can be readily substituted, by turning the screw then holding that pad in the assembly a sufficient number of turns to release the pad, and then, after removing the pad last-mentioned and applying the new pad, by turning said screw in the opposite direction to cause the same to be threadedly engaged with the new pad.

As shown in the case of the pad 12, any pad, mounted at either the front or rear of the carrier 10, in the one case to act as an anterior metatarsal support and in the other case to act as a tarsal support, can be so shaped around its axis of pivotal adjustment as to have around the latter various portions at different levels; with these different portions as numerous, and so individually shaped, and so relatively spaced, as may be desired. In order to make the drawing as simple as possible, and also incidently to illustrate one type of rear pad particularly efficacious when rotationally adjustable about even an axis concentric therewith for taking care of commonly encountered defective tarsal conditions, the pad 12 is shown as being rather simply varied in contour to present different heights at different portions; such portions establishing a high point 12a, an intermediate point 12b, and a low point 12c directly opposite said high point. As the parts are further shown by way of example, only the pad 12 is thus varied in contour, while the pad 11 is not; this pad 11 being shown as having merely a gently rounded upper convexity, as such a shaping of this pad is particularly efficacious when the pad is eccen-

trically rotationally adjusted about a properly selected axis for taking care of commonly encountered defective anterior metatarsal conditions. These pads 11 and 12, it will be understood, whether made circular as shown or otherwise shaped, can be variously contoured at their upper surfaces, and furnished in a great variety of such contours, as well as in a great variety of sizes, at comparatively trifling cost.

As the parts are shown, but here also solely by way of illustrative example, the pad 12 is concentrically pivotally mounted on the carrier, and the pad 11 is eccentrically pivotally mounted thereon. In a device carrying pads of these kinds, and with such pads so pivoted on the carrier, very many commonly encountered conditions can be met. Here, for instance, rotational adjustment of the pad 12 adjusts its parts of different height as desired circularly around the axis of its screw 17; and rotational adjustment of the pad 11 permits the same to be shifted laterally across the carrier and also longitudinally thereof. If increase of the general height of one or both pads is required so as in effect to reduce the height of the main-arch support 10a, or for any other purpose, and generally thicker pads are not available for use or are not desired to be used for any reason, shims (not shown) built up of paper, leather or other suitable material can be placed between one or both of the pads and the carrier. As above stated, the pad 12 is shown as of different levels in different portions on opposite sides of a concentric pivotal mounting, because a frequently encountered case is one where the tarsal or heel support required can be provided merely by rotational adjustment of such a pad. In other words, such a fairly simple shaping of a concentrically mounted pad 12 in quite a surprising number of cases takes care of tarsal or heel bone maladjustment of a common kind, that caused or aggravated by an excess of uric acid, and which is usually accompanied by a fallen or weakened main arch; and very often, consequently, the precise support needed for correcting any one of a great variety of tarsal maladjustments can be best obtained, while maintaining the remainder of the device exactly suited to the other defects in the foot, merely by thus rotationally adjusting such a pad as a pad shaped and mounted like the pad 12. Also as above stated, the pad 11 is here shown as an eccentrically pivotally mounted one of about the same height all over, because such a pad can be variously adjusted to take care of a great variety of anterior metatarsal maladjustments. In other words, in very many cases the action of the main-arch support 10a, when its effective height is adjusted where necessary by properly setting the heights of the two pads 11 and 12, is correct or incorrect according as the pad 11 presents an anterior metatarsal support properly or improperly spaced therefrom, and this space relation is correctly adjusted primarily if not entirely by a shifting of the center of pad 11 arcuately along a generally diagonal line across the carrier for a sufficient distance to locate the pad properly under the rear phalanges of the second and third toes. Consequently, the eccentricity of mounting of the pad 11, with its pivotal axis about one-quarter inch off center, is considered very important, whether or not the pad 12 be so mounted; and it is also considered important to have the pad 12 of such a contour as to present distinctly higher and lower portions around its pivotal mounting, particularly when said pad is concentrically mounted, as is preferred.

However, in some cases, it may be found desirable to embody one or both of the above characteristics of the pad 11 in the pad 12, and vice versa; and to have one pad thinner or thicker than the other; and to have one or both pads non-circular in outline; and in divers other ways to modify the pads or either of them, as, for instance, by having them adapted for rotational adjustment about any one of a plurality of axes, these axes differentiated sometimes as between concentricity and eccentricity, sometimes as between different extents of eccentricity, sometimes as between different locations on the carrier, sometimes as between different locations relative to a certain special height on a pad of varying heights, and so on.

For example, any pad for use either as a pad 11 or 12, that is, at the front or at the rear of the carrier 10, however such pad be shaped in outline or contoured at its top, can be provided in its backing with a plurality or even a multiplicity of various located tapped holes (for instance, as shown at 14a in Fig. 3) additional to but each precisely like the tapped hole illustrated in Fig. 5 as having a screw 17 threadedly engaged therewith, so that such screw can be thus engaged with any selected one of said holes. As an alternative or additional feature to that just above described, the carrier itself, at the front or rear end portion thereof through which a screw 17 is inserted for mounting a pad 11 or 12 over that end of the carrier, can have, instead of merely a single hole through which such screw is to be inserted as shown, any desired plurality or even multiplicity of variously located similar holes, so that said screw can be inserted through any selected one thereof. In aid of simplicity, merely two of the various possible groupings for such holes in the carrier ends are shown in the drawing,—to wit, two such holes, marked 10d, for the screw 17 for the rear pad 12, these holes spaced longitudinally of the carrier, and five such holes, marked 10e, for the screw 17 for the front pad 11, these holes in a symmetrical cluster. It will be understood that any number and arrangement of these holes can be arranged in either or both ends of the carrier; and, likewise, that any number and arrangement of extra tapped holes can be arranged in either or both of the pads 11 and 12.

In a device as herein described, a correctional foot appliance is provided which need be supplied in comparatively few sizes; which includes a carrier having a main-arch portion functional as a correct arch support without having to be raised or lowered; and which can readily have such main-arch support assisted properly in the work it has to do by merely properly adjusting and securing two rotatable auxiliary supports, one an anterior metatarsal support and the other a heel or tarsal support. In practically every case, as already stated, a dropped main arch is accompanied by a dislodgment of the rear phalange of the second or third toe, and unless a pad or the like is placed at the correct point under such toe or toes more harm than good may be done by even a correctly shaped and placed main-arch support. By the present arrangement not only is this condition adequately, simply and inexpensively taken care of, but also that individually varying but practically always accompanying maladjustment of the tarsal bones. By provid-

ing interchangeable pads, in which connection it is recommended that they be provided in three thicknesses, light, medium, and heavy, all possible situations can be easily met, except possibly for a rare exception; not only in first properly fitting the appliance, but in subsequently modifying the same either to take care of changed and usually improved conditions of the foot or to replace pads which have become worn or deformed by long continued use. The new appliance can be quickly changed from one shoe to another; and its other characteristics are such that any shoe retailer can carry in stock a suitable supply of plates or carriers and pads, and he, or the user, without the aid of technical or professional assistance, will find it quite a simple matter to make up the appliance exactly as required for any particular case, by selecting the proper carrier and the proper pads, and mounting the latter on the former on proper rotational axes, and adjusting and securing such pads at the proper angular adjustments.

As already stated, the pads need not be discs as illustrated, and can be of any outline desired; and it will of course be understood that the same can be constructed in any way and from any material or materials desired and suitable. Naturally, also, the carrier can be constructed of any material or materials desired and suitable. And generally, while I have indulged in considerable particularities of description, as to materials, di-

mensions, mountings and adjustments, it is to be emphasized that these are for purposes of illustration merely, and to express present preferences, and not intended to be made by way of limitation. The scope of protection contemplated is, accordingly, to be taken solely from the appended claims, interpreted as broadly as is consistent with the prior art.

I claim:

1. A correctional foot appliance presenting spaced tarsal, metatarsal and anterior metatarsal supporting elements, said appliance including a carrier having an elevated portion principally for metatarsal support, one of the two second mentioned elements being rotatably adjustable on said carrier, said rotatably adjustable element being also adjustable for varying its height on the carrier to vary the effective height of said elevated portion on the carrier. 80

2. A correctional foot appliance having a carrier provided with an elevated portion principally for metatarsal support, a rotatable disc-shaped pad located at each end of the carrier, at least one of said pads normally extending beyond that end of the carrier at which it is mounted, said pad being mounted eccentrically with respect to the carrier so that it may by rotative movement be more or less swung beyond the end of the carrier to increase or decrease the effective supporting length of the appliance. 90

DANTE V. MAZZOCCO. 105

35. A correctional foot appliance, including a carrier having an elevated portion principally for metatarsal support, a rotatable disc-shaped pad located at each end of the carrier, at least one of said pads normally extending beyond that end of the carrier at which it is mounted, said pad being mounted eccentrically with respect to the carrier so that it may by rotative movement be more or less swung beyond the end of the carrier to increase or decrease the effective supporting length of the appliance.

40. A correctional foot appliance, including a carrier having an elevated portion principally for metatarsal support, a rotatable disc-shaped pad located at each end of the carrier, at least one of said pads normally extending beyond that end of the carrier at which it is mounted, said pad being mounted eccentrically with respect to the carrier so that it may by rotative movement be more or less swung beyond the end of the carrier to increase or decrease the effective supporting length of the appliance.

45. A correctional foot appliance, including a carrier having an elevated portion principally for metatarsal support, a rotatable disc-shaped pad located at each end of the carrier, at least one of said pads normally extending beyond that end of the carrier at which it is mounted, said pad being mounted eccentrically with respect to the carrier so that it may by rotative movement be more or less swung beyond the end of the carrier to increase or decrease the effective supporting length of the appliance.

50. A correctional foot appliance, including a carrier having an elevated portion principally for metatarsal support, a rotatable disc-shaped pad located at each end of the carrier, at least one of said pads normally extending beyond that end of the carrier at which it is mounted, said pad being mounted eccentrically with respect to the carrier so that it may by rotative movement be more or less swung beyond the end of the carrier to increase or decrease the effective supporting length of the appliance.

55. A correctional foot appliance, including a carrier having an elevated portion principally for metatarsal support, a rotatable disc-shaped pad located at each end of the carrier, at least one of said pads normally extending beyond that end of the carrier at which it is mounted, said pad being mounted eccentrically with respect to the carrier so that it may by rotative movement be more or less swung beyond the end of the carrier to increase or decrease the effective supporting length of the appliance.

60. A correctional foot appliance, including a carrier having an elevated portion principally for metatarsal support, a rotatable disc-shaped pad located at each end of the carrier, at least one of said pads normally extending beyond that end of the carrier at which it is mounted, said pad being mounted eccentrically with respect to the carrier so that it may by rotative movement be more or less swung beyond the end of the carrier to increase or decrease the effective supporting length of the appliance.

65. A correctional foot appliance, including a carrier having an elevated portion principally for metatarsal support, a rotatable disc-shaped pad located at each end of the carrier, at least one of said pads normally extending beyond that end of the carrier at which it is mounted, said pad being mounted eccentrically with respect to the carrier so that it may by rotative movement be more or less swung beyond the end of the carrier to increase or decrease the effective supporting length of the appliance.

70. A correctional foot appliance, including a carrier having an elevated portion principally for metatarsal support, a rotatable disc-shaped pad located at each end of the carrier, at least one of said pads normally extending beyond that end of the carrier at which it is mounted, said pad being mounted eccentrically with respect to the carrier so that it may by rotative movement be more or less swung beyond the end of the carrier to increase or decrease the effective supporting length of the appliance.

75. A correctional foot appliance, including a carrier having an elevated portion principally for metatarsal support, a rotatable disc-shaped pad located at each end of the carrier, at least one of said pads normally extending beyond that end of the carrier at which it is mounted, said pad being mounted eccentrically with respect to the carrier so that it may by rotative movement be more or less swung beyond the end of the carrier to increase or decrease the effective supporting length of the appliance.
